[57] CLAIM

The ornamental design for an outsole for athletic shoe, substantially shown and described.

DESCRIPTION

FIG. 1 is a left side elevational view of an outsole for athletic shoe showing my new design, the broken line outlines of a shoe upper and subsole are environmental and form no part of the claimed design;

FIG. 2 is a bottom plan view thereof;

FIG. 3 is a right side elevational view thereof;

FIG. 4 is a front elevational view thereof;

FIG. 5 is a rear elevational view thereof;

FIG. 6 is an enlarged fragmentary view of one of the sole lugs as taken from line 6 of FIG. 2;

FIG. 7 is a cross-sectional view of the lug as taken from line 7—7 of FIG. 6;

FIG. 8 is a cross-sectional view of the lug as taken from line 8—8 of FIG. 6.

FIG. 1.

FIG. 2.

FIG. 3.

FIG. 4.

FIG. 5.

FIG. 6.

FIG. 7.

FIG. 8.
